UNITED STATES PATENT OFFICE.

JOHN BUCKLEY, OF LYNN, MASSACHUSETTS.

SHOE CONSTRUCTION.

1,210,041.

Specification of Letters Patent. Patented Dec. 26, 1916.

Application filed March 13, 1915. Serial No. 14,060.

To all whom it may concern:

Be it known that I, JOHN BUCKLEY, a citizen of the United States, and a resident of Lynn, county of Essex, State of Massachusetts, have invented an Improvement in Shoe Construction, of which the following description, in connection with the accompanying drawings, is a specification, like characters on the drawings representing like parts.

- 10 My invention relates to shoe construction and it is applicable to the so-called stitch-down boots and shoes, the McKay type of shoe and other types of shoes that require an inner sole, shoe upper and outsole whereby 15 the parts of these shoes may be assembled and united in a simple and expeditious manner, and in which the upper and inner sole may be united with or without the usual prior lasting process.
- 20 My invention improves the shoe as will be seen from the accompanying drawings and the description hereinafter.

In the drawings I have disclosed but a single embodiment of my invention in

25 which:—

- Figure 1 is a perspective of a shoe embodying my invention, with a portion of said shoe broken away. Fig. 2 is a greatly enlarged detail cross section on line 2—2 of Fig. 1. Figs. 3, 4, and 5 are modifications of the detail shown in Fig. 2 as will be more fully described herein. Fig. 6 is an enlarged detail cross section on about the same line 2—2 but extending clear across the shoe and 35 showing a modification of the structure in Fig. 2. Figs. 7 and 8 are enlarged details of a welt embodying in part my invention. Fig. 9 is a plan view of the blank from which the insole shown in Fig. 10 is produced.
- 40 Fig. 10 is a perspective view of my improved insole. Figs. 11, 12 and 13 are detail sections illustrating the insole cross section and the manner of uniting the insole with an upper and my improved welt. Fig. 14 is a modified form of the blank in Fig. 9 with the guiding flange portion omitted about the heel of the insole.
- 45

The terms employed herein are used in the generic and descriptive sense and not primarily for the purpose of imposing limitations upon my invention.

- My invention comprises in part a doubled or folded welt 10 of the character shown by the detail views thereof in the drawings. 55 This doubled or folded welt, or double and folded welt is made up of a strip of leather

of substantially twice the width of the finished size of welt desired or twice the width of the present type of welt and it is then creased along the middle 11 thereof to form 60 what may be termed herein as flanges 14 and 15 of equal width.

The doubled or folded welt shown in Figs. 7 and 8 may be of lighter weight or even of a thinner grade of leather than that now employed for the single strip or strip welt known in the art, but when doubled or folded as shown herein said welt will present substantially the same strength and thickness of "between substance" as now employed in the case of the said single strip welt. If desired the welt may also be provided with a score or groove 16 as shown in Fig. 8 for the purpose of receiving stitching or other fastenings hereinafter described. 70 This welt may be carried about both sides of the shank, both sides of the fore part and about the toe of the shoe in substantially the same manner as heretofore in the employment of the single strip like welt.

80 In carrying out my invention I preferably employ an insole as shown in Figs. 9 to 14 inclusive comprising a main sole shaped body portion 20 and a guiding flange 21 extending at right angles to the surface of the 85 said body portion 20. As shown in the figures illustrating the same the insole 20 is produced from a blank somewhat larger than the usual size of the sole desired and along the dotted line 23 there is provided a 90 score or groove 24. This score or groove is formed by slitting partially through the material along the line 24 on Fig. 9 at the tread face of the sole and perpendicular to the said sole which permits the turning 95 of the guiding flange 21 in an angular position as shown in Fig. 11. Before turning, the flange 21 is provided with slits or notches 100 extending from said score or groove 24 to the edge of the flange 21 the whole being shaped preferably by suitable dies to produce the insole shown in Fig. 10. The words "slits or notches" are used synonymously to describe the character of the severance about the guiding flange 21. Said 105 slits more nearly presenting a notch like form around the more narrowed parts of the insole, as for example, the heel and the toe, see Figs. 10 and 11.

If desired the guiding flange 21 may be 110 omitted about the heel seat portion 28, see Fig. 14 and it may also be omitted along

the shank portion 30 in some types of shoes.

The guiding flange 21 is preferably beveled or skived as shown in Figs. 11, 12 and 13 so that in the finished edge of the shoe it will practically or wholly be invisible and the notches or slits will not show. In the manufacture of the McKay or other types of shoe the said guiding flange will not form a ridge beneath the insole.

10 The upper 31 of the shoe is preferably "cut to size" so that the outer or bottom edge 39 may be brought in line with the edge of the flange 21 of the insole and the said flange will form a guide against which the edge of the upper may be laid and by means of which it may be positioned and gaged during the sewing operation whether the said parts are on a last or not.

15 20 The guiding flanges 21 in addition to forming a guide against which the edge of the upper is placed and positioned also assists in guiding the work with relation to the operation of the needle as the presser-25 foot of the sewing machine may rest in the angle formed between the body portion 20 of the insole and the inner face of the guiding flange 21. This is desirable inasmuch as the guiding flange 21 provides a means 30 whereby the edge of the upper may be accurately positioned and guided with relation to the stitch forming mechanism of the sewing machine in placing the line of stitching 32 and in addition the welt 10 may also 35 be accurately guided at the proper place along the outer surface of the shoe upper 31.

A sock lining 33 may if desired, be secured to the insole by the stitching 34 about the marginal portion thereof as shown in 40 Fig. 12. The said sock lining will conform in shape to the bottom edge of the last and to the margin of the score or groove 24 about the said insole.

45 If desired a "skipper" or thin intermediate sole may also be employed as shown in Figs. 2 and 4. This thin intermediate sole is of light thin tough leather and it may be secured by a line of stitching 35 to the outstanding edges of the upper and the flange 50 21 as shown in Fig. 5. In lieu of the above method of securing the said "skipper" to the said upper and insole it may be secured by a line of stitching to the lower flange 15 of the welt previous to which the flange 21 of the insole and the edge of the upper have been trimmed down close to the line of stitching as shown in Fig. 4. When the upper 31 is laid against the guiding flange 21 and fastened thereto by the line of stitching 55 60 65 38 the welt 10 may then be positioned so that the fold 11 lies substantially along the score or groove 24 and the operator takes the insole, the upper and the welt and presents them to the action of a straight or curved needle sewing machine the needle of which

passes the stitching 36 through the guiding flange 21, through the upper and through the welt substantially along the fold 11. After the insole, the upper and the welt 10 have been united by the line of stitching 36 70 and if lasting has not been performed prior thereto a last of the desired shape and size may now be forced into the shoe to shape the upper and cause it to conform closely to the outlines of the said last. 75

In making the so-called "welt" shoe embodying my invention the upper and insole may be assembled and united in any suitable and preferred manner herein described, and the double or folded welt herein is preferably united to the above by the line of stitching 36 then after the necessary operations are performed to put the shoe in condition to receive the outsole, the flanges 14 and 15 are brought together and may be 80 cemented one to the other.

When the welt 10, the upper 31 and the insole have been united as above stated the flanges 14 and 15 of the said welt inclose the line of stitching 36 used to unite it with 90 the said insole and the said upper.

The guiding flange 21 and the upper may be turned inward and against the under face of the insole, or they may be trimmed off close to the lines of stitching 32 and 36 as 95 shown in Figs. 3 and 13. In the latter case the remaining portions of the upper and the flange 21 may be slightly flattened down by beating the same. The insole, upper and welt now joined are secured to the outsole 100 41 by a line of stitching 37 passing through both "between substances" of the welt and through the said outsole.

In the event that it is desired to make 105 stitch-down shoes as in Figs. 2 and 5 the edge of the upper and the guiding flange 21 of the insole are turned downward and outward in the plane of the bottom of the last and an outsole 41 is secured to the outstanding double welt 10, to the said edge of the 110 upper and to the outstanding edges of the guiding flange 21 by means of a line of stitching 38 and the sole is finished in the usual manner of finishing stitch-down shoes. 115

When it is desired to make a shoe after the upper the insole and the said welt have been united by the stitching 32 and 36 and after the introduction of the last therein it will be understood that the edge of the upper and the guiding flange 21 may be turned inward over the bottom of the insole, or turned downward and outward as in Figs. 2 and 5 or may be trimmed off close to the lines of the aforesaid stitching as shown in 120 Figs. 3 and 4 and a filling material if desired may be laid upon the surface of the insole within the inturned edges of the upper and flange 21 or between the trimmed edges of the upper and insole flange 21 after 125 which the outsole is "laid" and may be tem- 130

porarily secured in any, or in the usual manner. Thereafter, the outsole, the insole and the upper and the welt the flanges of which have been brought together to form a 5 single "between substance" are united by a line of wire nails or by stitching 37 formed by the usual wax thread lock stitch straight or curved needle shoe sewing machine.

In case the insole is produced without 10 any portion of the guiding flange 21 thereabout the upper about such portion from which said flange has been omitted will be "lasted over" in the usual manner. If for example the guiding flange only extends 15 about the toe and fore part of the shoe and there is no guiding flange 21 about the shank and heel of the insole said stitchings 32 and 26 will then unite the insole, the welt and the upper about the said fore part and toe 20 and the upper along the line of the shank, is then lasted over in the said usual manner.

It is of course understood that shoes produced in the manner hereinbefore described 25 may have the usual stiffenings, linings and other parts commonly going to make up a shoe and that they will be of the usual form and arrangement.

While preferably I employ an insole of the type illustrated and described herein 30 nevertheless in carrying out my invention

with relation to the double or folded welt I may employ any other suitable insole adapted to perform the functions and objects of the insole described herein.

I have described herein one embodiment 35 of my invention; but it is to be understood that the latter is not essentially limited to the specific details of construction and organization of said embodiment, since the same may be varied without departing from 40 the proper scope of the claim.

Claim—

A shoe construction comprising an upper, an insole provided with a tapering flange 45 adapted to be turned into any angular relation with respect to the body of the insole in order that said upper and insole when joined may be utilized for different types of shoes, said insole flange being provided with slits or notches, and a strip of material folded to form a double welt and united to said upper and insole by a line of stitches substantially along the fold of the welt. 50

In testimony whereof, I have signed my name to this specification, in the presence of two subscribing witnesses.

JOHN BUCKLEY.
